UNITED STATES PATENT OFFICE

124,069

DESIGN FOR A WALLPAPER

Herbert Fasold, New York, N. Y.

Application October 24, 1940, Serial No. 96,042

Term of patent 3½ years

To all whom it may concern:

Be it known that I, Herbert Fasold, a citizen of the United States of America, residing in New York city, county of New York, and State of New York, have invented a new, original, and ornamental Design for a Wallpaper, of which the following is a specification, reference being had to the accompanying drawing, forming part thereof, wherein the figure of the drawing is a plan view of a wallpaper showing my design.

I claim:

The ornamental design for a wallpaper, substantially as shown.

HERBERT FASOLD.
